(57) **CLAIM**

The ornamental design for a display panel or portion thereof with a transitional mixed reality graphical user interface, as shown and described.

DESCRIPTION

FIG. 1 is a front view of a display panel or portion thereof with a transitional mixed reality graphical user interface component showing a first image in a sequence of our design;

FIG. 2 is a front view of a display panel or portion thereof showing a second image thereof;

FIG. 3 is a front view of a display panel or portion thereof showing a third image thereof;

FIG. 4 is a front view of a display panel or portion thereof showing a fourth image thereof; and,

FIG. 5 is a front view of a display panel or portion thereof showing a fifth image thereof.

The subject matter of the present disclosure includes graphical user interface components present within a mixed reality interface. The subject matter of the present disclosure includes a process or period during which one computer graphical user interface component changes into another. In particular, the appearance of the image transitions between the images shown in FIGS. 1 to 5. This process or period in which one computer graphical user interface component transitions into another computer graphical user interface component forms no part of the claimed design.

The outermost broken line rectangles illustrating a display panel of a computing device or portion thereof are included for the purpose of illustrating environmental structure and form no part of the claimed design. The broken lines illustrating portions of the graphical user interface are included for illustrating environmental aspects of a display panel or portion thereof showing a transitional mixed reality graphical user interface and form no part of the claimed design.

1 Claim, 5 Drawing Sheets
